(57) **CLAIM**

The ornamental design for a bottle pourer, as shown and described.

DESCRIPTION

FIG. 1 is a perspective view of a first embodiment of a bottle pourer of the present invention with the bottle pourer shown in a closed condition;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and

FIG. 8 is a perspective view thereof with the bottle pourer of the first embodiment shown in an open condition;

FIG. 9 is a perspective view of a second embodiment of a bottle pourer of the present invention with the bottle pourer shown in the closed condition;

FIG. 10 is a front view thereof;

FIG. 11 is a left side view thereof;

FIG. 12 is a right side view thereof;

FIG. 13 is a rear view thereof;

FIG. 14 is a top view thereof;

FIG. 15 is a bottom view thereof; and,

FIG. 16 is a perspective view thereof with the bottle pourer of the second embodiment shown in an open condition.

The broken lines shown in the drawings represent portions of the bottle pourer and form no part of the claimed design.

1 Claim, 14 Drawing Sheets
